UNITED STATES PATENT OFFICE.

JOSEPH GILLET, OF MILWAUKEE, WISCONSIN, ASSIGNOR TO THE MILWAUKEE MANUFACTURING COMPANY, OF SAME PLACE.

FRICITION-PULLEY.

SPECIFICATION forming part of Letters Patent No. 615,268, dated December 6, 1898.

Application filed January 17, 1898. Serial No. 666,885. (No model.)

To all whom it may concern:

Be it known that I, JOSEPH GILLET, of Milwaukee, in the county of Milwaukee and State of Wisconsin, have invented a new and useful 5 Improvement in Friction-Pulleys, of which the following is a description, reference being had to the accompanying drawings, which are a part of this specification.

My invention has relation to improvements 10 in friction-pulleys of that class designed for starting, stopping, and reversing rotary motion.

It is the object of the invention to provide an improved form of pulley-clutch in which 15 a simple means is employed for clutching and unclutching the pulley to the shaft and at the same time to provide for preventing the pivoted levers from flying outwardly by centrifugal force, and thereby clutching the pulley at 20 a time when it is desired that said pulley should remain loose on the shaft.

With the above primary objects in view the invention consists of the improved construction and combination of parts or their equivalents, as hereinafter more fully set forth.

In the accompanying drawings, Figure 1 is a side elevation of a pulley equipped with my improvements. Fig. 2 is a sectional view of Fig. 1; and Fig. 3 is an end view of the longitudinal movable part, showing the shaft in section.

Referring to the drawings, the numeral 4 indicates a shaft on which is loosely mounted a pulley 5. A plate 6 extends across the pulley from one point of the inner side of its periphery to the opposite point thereof, but not connected to the pulley at either of said points. To this plate are pivoted the ring-segments 7 7'. The segment 7 is pivoted at 40 the point 8 and the segment 7' at the point 8'. The unpivoted end of segment 7 is provided with an elongated slot 9, through which a screw-bolt 10 passes and enters the plate, and the ring-segment 7' is provided at its unpivoted end with a similar elongated slot 9', to which a screw-bolt 10' passes and likewise enters the plate. Near the unpivoted ends of the segments 7 7' are formed, in the inner edges of said segments, recesses 11 11', respectively. The plate 6 is formed or provided with a projecting hub 12. Through this hub

pass set-screws 13, which connect said hub to the shaft, and thus hold the hub and the plate from which it projects to revolution with the shaft. The plate 6 is provided at diametrically opposite points with slots 14 14, which extend to the hub 12 and communicate with branch slots 15 15, running longitudinally of the hub.

Pivoted to the plate 6 are levers 16 16', the short arms of which extend into the recesses 11 11' of the segments 7 7'. The inner ends of these levers are extended at right angles, as indicated by the numerals 17 17', respectively, and pass into the slots 15 15 of the hub.

Parts similar or substantially similar to those hereinbefore described have been before used in friction-pulleys, and hence I do not make any claim thereto, except in so far as they coact or combine with my improvements, which will now be specifically described.

It will be noticed that opposite ends of the angular extension 17 of the lever 16 are formed with beveled edges 18 18' and that the opposite ends of the angular extension 17' of lever 16 are formed, respectively, with reversely arranged beveled edges 19 19'.

Mounted on the shaft 4 is a sleeve 20. This sleeve is made rotatable with the shaft and is longitudinally movable thereon by means of a feather 21 on the shaft engaging a complementary groove of the sleeve. Longitudinal movement may be imparted to the sleeve by means of a lever 22, provided with a forked end, engaging an annular groove 23 in the sleeve. Projecting from opposite points of this sleeve toward the pulley are arms 24 and 25. Arm 24 is provided with two branches 26 and 27. The under edge of branch arm 26 is provided with a straight portion 28, which is shown in Fig. 2 as resting on the upper surface of the angular extension 17 and is formed just back of said straight edge with a beveled edge 29, which is adapted when the sleeve is moved toward the pulley to match and register with the beveled edge 18' of the angular extension 17. The extremity of the lower shorter branch arm 27 is formed with a beveled edge 30, which as the sleeve is moved toward the pulley is adapted to match and register with the beveled edge 18 of the an-

gular extension 17. The arm 25 is likewise formed with two branch arms 31 and 32, of similar construction to the arms 24 and 25—that is to say, arm 31 is provided with a straight edge 33, which edge in Fig. 2 is shown as resting on the under surface of the angular extension 17', and with a beveled surface 34, which is adapted to register with the beveled end 19' of the angular extension 17', while the upper shorter arm 32 is provided at its extremity with a beveled edge 35, which is adapted to register with the beveled end 19 of the angular extension 17'.

To limit the movement of the sleeve 20 in a direction away from the pulley, I mount on the shaft 4 a collar 36, held by means of a set-screw. Another collar 37 is similarly mounted on the shaft adjacent to the hub of the pulley and serves to prevent said pulley from end-wise movement in one direction.

In the operation of my invention if it is supposed that the pulley is running loosely on the shaft 4 and it is desired to tighten or clutch said pulley to the shaft the sleeve 20, by means of the lever 22, is moved longitudinally on the shaft, so as to throw the arms of said sleeve toward the pulley. The straight edges 28 and 33 of the arms 26 and 31 will then ride along the corresponding surfaces of the angular extensions of the levers 16 16' and cause the beveled ends 30 and 35 of the arms 26 and 31 to engage the corresponding bevels 18 and 19 of the angular extensions. The slots 14 of the plate 6 of course offer no obstruction to the movement of the arms 26 and 31 in this direction. The effect of the engagement of the bevels just referred to is to turn the levers 16 16' on their pivots, (the angular extensions 17 and 17' passing into the spaces between the respective branch arms of the arms 24 and 25,) so that the short arms thereof will force apart the rings 7 7'. This will necessarily expand the ring-segments until they bind against the inner surface of the periphery of the pulley, and thereby cause said pulley to rotate with the shaft 4. On the reverse movement of the sleeve 20 the bevels 29 and 34 act on the beveled surfaces 18' and 19' of the angular extensions of the lever, and thereby act to turn back the levers 16 16' to their normal positions, and consequently unclutch the segment-rings from engagement with the rim of the pulley, thereby permitting the pulley to be again loose on the shaft. The continued movement of the sleeve 20 will draw the straight edges 28 and 23 onto the corresponding edges of the angular extensions 17 and 17' to the positions shown in Fig. 2.

An important feature of my invention is the provision of the arms 26 and 31, which when the parts are unclutched and the pulley is therefore loose on the shaft hold the angular extensions of levers 16 16' down to place and prevent their swinging outwardly by centrifugal force, so as to turn said levers 16 16', and thus bind or clutch the segments

7 7' at a time when it is not desired that such segments should bind or the pulley rotate with the shaft. Springs for this purpose are objectionable, owing to the fact that in order to successfully prevent the turning of the levers when the pulley is loose very stiff springs are necessary, and consequently to force the sleeve 20 toward the pulley would require considerable power. Besides, springs very soon wear and lose their power. My improved construction provides an absolute safeguard against the clutching of the segments at times when it is not desired that the clutching should be effected, and at the same time a free and easy movement of the sliding sleeve is obtainable.

What I claim as my invention is—

1. The combination, of a shaft, a pulley mounted loosely thereon, a plate mounted on the shaft and provided with a hub portion said hub portion having a groove or slot therein, a clutch member within the pulley and adapted to be engaged with and disengaged from the rim of the pulley, a lever pivoted to the plate and having one arm engaging the clutch member, a longitudinally-movable sleeve mounted on the shaft, and arms extending from said sleeve, the inner arm engaging the slot of the hub, and the outer arm adapted, when the pulley is unclutched, to bear against the inner end of the lever, and each of said arms provided with a beveled edge, the beveled edge of one arm adapted to engage a correspondingly-beveled edge of the inner end of the lever on the movement of the sleeve toward the pulley, whereby the lever is turned so as to throw the clutch member into engagement with the pulley, and the beveled edge of the other arm adapted to engage a registering bevel of the lever, in order to unclutch the clutch member from the pulley.

2. The combination, of a shaft, a pulley mounted loosely thereon, a plate mounted on the shaft, a clutch member within the pulley, a lever pivoted to the plate and having one arm engaging the clutch member, a longitudinally-movable sleeve having an arm projecting therefrom, said arm adapted, when the clutch member is out of clutch to bear against the inner end of the lever and prevent the turning of said lever by centrifugal force, and means, when the sleeve is moved toward the pulley, for turning the lever on its pivot so as to throw the clutch member into engagement with the pulley, and, when the sleeve is moved away from the pulley, for turning the lever in the opposite direction to unclutch the clutch member.

3. The combination, of a shaft, a pulley mounted loosely thereon, a plate mounted on the shaft and provided with a hub, said hub portion having a groove or slot therein, clutch-segments within the pulley and adapted to be engaged with and to be disengaged from the rim of the pulley, levers pivoted to the plate, and each having one arm engaging a clutch-segment, a longitudinally-movable sleeve

mounted on the shaft, and sets of arms extending from the sleeve, the inner arm of each set engaging the slot of the hub, and the outer arm of each set adapted, when the pulley is unclutched, to bear against the inner end of the lever, and each arm of a set provided with a beveled edge, the beveled edge of one of said arms adapted to engage a corresponding beveled edge of the inner end of the lever on the movement of the sleeve toward the pulley, whereby the lever is turned so as to throw the clutch-segments into engagement with the pulley, and the beveled edge of the other arm of each set adapted to engage a registering bevel of the lever, in order to unclutch the segments from the pulley.

4. The combination, of a shaft, a pulley mounted loosely thereon, a plate mounted on the shaft and provided with a hub, said plates having slots at opposite points communicating with slots in the hub, clutch-segments within the pulley and adapted to be engaged with and to be disengaged from the rim of the pulley, levers pivoted to the plate, and each having one arm engaging a clutch-segment, and the ends of its opposite arm provided with an extension at an angle there-

from, a longitudinally-movable sleeve mounted on the shaft, and sets of arms extending from the sleeve, the inner arm of each set 30 engaging the slot of the hub, and the outer arm of each set adapted, when the pulley is unclutched, to bear against the angular end of the lever, and each arm of a set provided with a beveled edge, the beveled edge of one 35 of said arms adapted to engage a corresponding beveled edge of the angular end of the lever, on the movement of the sleeve toward the pulley, whereby the lever is turned so as to throw the clutch-segments into engagement 40 with the pulley, the angular end of each lever after the disengagement of these bevels passing into an increased space between the arms of a set, and the beveled edge of the other arm of each set adapted to engage a registering bevel of the angular extension of the lever, in order to unclutch the segments from the pulley.

In testimony whereof I affix my signature in presence of two witnesses.

JOSEPH GILLET.
